(57) **CLAIM**

The ornamental design for a sealing container for household use, as shown and described.

DESCRIPTION

1. Sealing container for household use

1.1 : Perspective

1.2 : Front

1.3 : Back

1.4 : Left

1.5 : Right

1.6 : Top

1.7 : Bottom

This design provides a sealing container for household use to store food and goods; Fig. 1 is a perspective view; Fig. 2 is a front view thereof; Fig. 3 is a rear view thereof; Fig. 4 is a left side view thereof; Fig. 5 is a right side view thereof; Fig. 6 is a top view thereof; Fig. 7 is a bottom view thereof; The broken lines in the drawings depict portions of the sealing container for household use that form no part of the claimed design.
